UNITED STATES PATENT OFFICE.

GEORGE W. SHARER, OF TERRE HAUTE, INDIANA.

DRIER.

SPECIFICATION forming part of Letters Patent No. 315,348, dated April 7, 1885.

Application filed July 26, 1884. (No model.)

To all whom it may concern:

Be it known that I, GEORGE W. SHARER, a citizen of the United States, residing at Terre Haute, in the county of Vigo and State of Indiana, have invented certain new and useful Improvements in Driers; and I do hereby declare the following to be a full, clear, and exact description of the invention, such as will enable others skilled in the art to which it appertains to make and use the same.

My invention relates to driers for all kinds of articles, but particularly to that class in which brick, pottery, tile, lumber, and similar objects are deprived of their moisture.

The object of the invention is to make a drier that will combine cheapness in construction and utility in the arrangement of parts, so that in working the drier the operator can take every advantage to facilitate his work.

My invention therefore consists of constructions and combinations, all as will hereinafter be described and claimed, reference being had to the accompanying drawings, in which—

Figure 1 represents a perspective view of my improved device; Fig. 2, a longitudinal section; Fig. 3, a vertical section through the chimney, breaching, and flue A². The side walls are also shown in section on a line through chimneys a. Fig. 4 is a partial plan and section, the left-hand side showing a section through the flue A² and furnace, and the right-hand side showing the floor of drying-chamber in elevation and the platform broken away.

A represents the drying-chamber; B, the furnace; C, the distributing-vault of the furnace; D, the air-passage; E, the chimney, and F the breaching connecting the chimney and drying-chamber. The drying-chamber A is of oblong shape, and may be between sixty and one hundred feet in length, from five and one-half to six feet in width, and four and one-half feet in height.

It is obvious that variations from these dimensions can be made without departing from my invention; but those stated are preferred, as I have found by actual practice that they produce the desired result. The side walls, A' A', of the chamber are hollow to form flues a', communicating above with chimneys

a, and below with flue A², beneath the floor of the chamber. The flue A² is divided into several longitudinal smaller flues, a², the outer ones of which communicate directly with flues a', so that the side walls will be heated, and thus prevent the articles in the chamber and nearest said wall from being chilled, as would be the case if this provision were not made; or, in other words, it enables the operator to keep the chamber at an even temperature, as the heated side walls protect the chamber from lateral radiation. The bottom of the drying-chamber is the top wall of the flue A², which is made of brick or other suitable material, covered with a thin layer of cement to keep the smoke, sparks, and flame out of the drying-chamber, and at the same time present a surface that will rapidly radiate the heat.

It is obvious that the bricks could be covered with metal or other substance and produce the same result. The floor of the drying-chamber may be level, or slightly inclined from the rear end to a point near the front end, where it terminates in an opening, D', which will hereinafter be described. The flue A² at this point is deflected obliquely to the distributing-vault, and its upper wall serves as part of the bottom of the air-passage D. This passage is formed above the furnace, and its upper wall, D², forms a continuation of the bottom of the drying-chamber from the opening D', which is bridged by a track extending through the drier and terminating at any suitable point for the operation of the carriages A⁴, that contain the material to be dried. The passage D is preferably divided into a number of smaller longitudinal passages, d, which extend from opening D' to the front end of the furnace, where said passage is provided with a register consisting of a perforated plate, d', and a perforated slide, d'', the openings of which can be made to register with the openings in the plate, so that the amount of air entering the passage D can be regulated. The air entering through these perforations absorbs the heat radiated from the furnace and flue A², and enters the drying-compartment through opening D' as a hot-blast, thereby preventing injury to the articles being dried, as would be

the case if the blast were cold. It also prevents the ware at the end of the chamber nearest the furnace from becoming overheated and injured, as would be the case if no air were used. Each end of the furnace is provided with a door, A⁵ and A⁶, which may move vertically or swing outwardly for the admission and exit of the cars. At the rear end is an opening, D³, which communicates with the 15 breaching F. In front of this opening D³ is a pendent swinging door, A⁷, having its lower end near the bottom of the drying-chamber, so that the hot air which enters through opening D', and by reason of its lightness rises in 20 the chamber, will force the heavier vapor out of the chamber before it can make its exit beneath the door. In this way the door retards the heated air and also prevents the article near the bottom from being dried too rapidly 25 by the heat radiated from the flue A². The door A⁷ is preferably pivoted by its upper end, so that when the cars have been pushed into the chamber it will automatically fall in place and forms with door A⁶ a passage, A⁸, 30 for the escape of vapor into the breaching. This passage A⁸ also serves to protect the articles from being chilled when door A⁶ is opened for the admission of another car or for other purposes. To still further protect this end of 35 the drying-chamber, a transverse flue, A⁹, in which the flue A² terminates, is placed below the bottom of passage A⁸. This flue A⁹ is provided with a soot-chamber, a⁰, provided with a suitable opening for the withdrawal of the 40 soot when a sufficient quantity has collected. One end of the flue communicates with the chimney E, placed at one side of the drying-chamber on a line with the breaching F, which 45 opens therein. The chimney is provided with a partition, F', which does not extend quite to the top. The products of combustion pass up one side of the partition, and the suction caused by their passage draws or sucks the vapor through the breaching, and thus accelerates the draft through the drying-chamber. 50 The furnace, as before stated, is below the front end of the passage D. For a drying-chamber of the dimensions above mentioned the grate-surface is preferably four by two 55 and one-half feet. The rear end is elongated to the full width of the drying-chamber to make the heat-distributing vault C, with which, as before stated, the flue A² is connected, and enters it about ten or eleven inches above the 60 grate-level, leaving a chamber, c, above for the products of combustion. The top of the vault is provided with a fire-clay tile, c', surrounded by a layer of brick. The furnace and flue are also provided with similar tile, b and b', which radiate the heat into passage D, where it is absorbed by the air. 65 In the above description it will be noted that only one drying-chamber has been described. When it is desired to use more than one, they may be advantageously separated by a thin wall, A¹⁰, which will be readily heated by the hot air. If more than one drying-

chamber be used, the breaching can be made with a sufficient number of passages to carry off the vapor from each chamber separately. 70

Upon inspection of the drawings it will be seen that the bottom of flue A² is on the ground-line; also the bottom of the passage D, the top of which is on the same plane as the bottom of the drying-chamber. By these means the operation of loading and unloading the cars is facilitated, as the operator can load the cars without having to elevate the material to any considerable height. By placing the furnace below the ground level and beneath the passage D, the top wall of which serves as a platform, the operator is protected from the heat which otherwise would arise and make his position uncomfortable. 75

The operation of the device is as follows: 80 After the fire has been started, air is heated in passage D and passed into the drier, where it is further heated by the radiation from the bottom and side walls. The loaded cars are now pushed in at the rear end at such periods 85 as may be deemed necessary. The material on the car first put in will necessarily be dried the first, as it is constantly advancing toward the hottest or dryest part; or, in other words, the hot air entering the front end of the drying-chamber attacks the front car first and gathers vapor which more or less reduces the temperature as it advances toward the rear end, where it escapes under the hanging door into the breaching. As soon as the contents of 90 one car have become dried, the latter is drawn out at the front end and another car pushed in at the rear end. By this means I am enabled to keep the drier in continuous operation. 95

What I claim as new is—

1. In a drier, the combination of a drying-chamber having an inlet and outlet for air between its ends, a furnace having a flue which forms part of the bottom of the drying-chamber, and an air-passage above the furnace, its upper wall forming a continuation of the bottom of the drying-chamber and having its outlet within said drying-chamber, substantially as described. 105

2. In a drier, the combination of a drying-chamber having an inlet and an outlet for air between its ends which are provided with doors, a furnace having a flue part of which is deflected below the bottom to form opening D', and the remainder forming the bottom of said drying-chamber, and an air-passage above the furnace and having its upper wall overlapping the deflected part of the flue to form a continuation of the bottom of said drying-chamber 115 provided with a track for bridging said opening D', substantially as described. 120

3. In a drier, a drying-chamber having door A⁵ at one end, door A⁶ at the other, intermediate door, A⁷, passage A⁸, formed by doors A⁶ 125 and A⁷, and the opening D' in the bottom of the drying-chamber, substantially as described. 130

4. In a drier, the combination of a drying-

chamber having hollow side walls forming flues A' , opening D' , and passage A^8 , of a series of flues forming the bottom of said drying-chamber, the outer ones of which are connected with the flue-space in the hollow walls of said drying-chamber, substantially as described.

5. In a drier, the combination of several drying-chambers separated from each other by a thin partition, and each having doors A^5 , A^6 , and A^7 , and passage A^8 , a breaching having a separate passage for the several drying-chambers, and a chimney with which the breaching communicates, substantially as described.

15 6. In a drier, the combination of a drying-chamber having a flue in its bottom and provided with doors A^5 , A^6 , and A^7 , and passage

A^8 , a flue, A^9 , connected with said passage, a chimney divided into two parts by a vertical 20 partition, one part connected with said flue A^9 , and a breaching connected with passage A^9 and the other part of the chimney, substantially as described.

7. In a drier, the combination of a furnace 25 having a distributing-vault and flues opening into said vault, and the tops of said furnace and vault provided with tile, and an air-passage located above said tile, substantially as described.

In testimony whereof I affix my signature in presence of two witnesses.

GEORGE W. SHARER.
